UNITED STATES PATENT OFFICE.

WILLIAM P. WHITLEY, OF ST. LOUIS, MISSOURI, ASSIGNOR TO RAWLINGS MANUFACTURING COMPANY, OF ST. LOUIS, MISSOURI, A CORPORATION OF MISSOURI.

ATHLETIC GUARD.

Application filed December 28, 1925. Serial No. 77,932.

This invention relates to athletic guards of the type that comprise a substantially rigid and inflexible protecting element of concavo-convex shape in transverse cross section, provided on its rear side with a taut, transversely-disposed member whose function is to hold said protecting element spaced away from the part of the wearer's body that is to be protected and also to act as a cushion 10 that absorbs a shock or blow on said protecting element.

The protecting element of such an athletic guard is usually formed from hard fibre and the transversely-disposed member on the rear side of said protecting element is usually formed from a piece of wide webbing stretched taut and secured at its ends to the side edges of the protecting element. Consequently, if the protecting element warps 20 in such a way as to bring the side edges of same closer together, or if said protecting element is subjected to a blow or pressure which tends to increase the transverse curvature of said element, the piece of webbing 25 that extends transversely across the rear side of said protecting element is apt to become slack, and thus fail to effectively absorb a shock or blow on the protecting element.

The object of my invention is to provide 30 an athletic guard of the general type mentioned, which is equipped with a means that effectively prevents the protecting element of the guard from assuming such a shape or condition as to materially reduce the tautness of the transversely-disposed member on the rear side of said element.

To this end I have devised an athletic guard which consists of a protecting element of approximately concavo-convex shape in 40 transverse cross section formed from material that is substantially rigid and inflexible, a shock absorbing means at the rear side of said element formed from a piece of webbing or the like that is stretched taut transversely 45 of said member and secured to the side edge portions of same, and a non-stretchable stay drawn taut across the front side of said protecting element and secured at its ends to the side edge portions of same so as to prevent 50 said protecting element from curling up or assuming such a condition as to materially reduce the tautness of the shock absorbing member on the rear side of said element.

Figure 1 of the drawings is a rear eleva-

tional view of an athletic guard constructed 55 in accordance with my invention.

Figure 2 is a front elevational view of said guard.

Figure 3 is a longitudinal sectional view of said guard, taken on the line 3—3 of Figure 60 1; and

Figure 4 is a transverse sectional view of said guard, taken on the line 4—4 of Figure 1.

My invention is applicable to thigh guards, 65 shin guards, shoulder guards and various other kinds of athletic guards that are adapted to be positioned in a pocket in a garment, laced to a garment, or attached directly to the portion of the wearer's body 70 which it is desired to protect, and while I have herein illustrated my invention embodied in a thigh guard of the type that is arranged in a pocket on the inside of the leg 75 of a pair of foot ball pants, I wish it to be understood that the particular purpose for which the guard is used is immaterial and also that the protecting element of the guard can be shaped in various ways and various 80 means can be used for holding the guard in operative relationship with the part of the wearer's body that is to be protected, without departing from the spirit of my invention.

Referring to the drawings which illustrate 85 the preferred form of my invention, A designates the protecting element of the guard which preferably consists of a substantially rigid or inflexible member of substantially 90 concavo-convex shape in transverse cross section formed from a piece of hard fibre or other suitable material that is bowed or curved slightly intermediate its side edges, B designates a transversely-disposed member 95 on the rear side of the element A that is used to hold said element spaced away from the part of the wearer's body that is to be protected and also to form a cushion that absorbs a shock or blow on said protecting element, and C designates a non-stretchable stay drawn tightly across the front side of the protecting element A so as to prevent said protecting element from curling up or assuming such a condition as to materially reduce the tautness of the shock absorbing member B on the rear side of said protecting element. The shock absorbing member B is 100 preferably formed from a piece of wide web- 105

bing or other suitable non-stretchable fabric that is stretched taut transversely of the protecting element A and secured at its ends to the side edge portions of said protecting element in any suitable way, as for example, by stitches 1, as shown in Figure 1. The stay C on the front side of the protecting element A is also preferably formed from a piece of wide webbing or other suitable non-stretchable fabric whose ends are connected to the side edge portions of the protecting element by the stitches 1 that secure the ends of the shock absorbing member B to the protecting element. With such a guard, any tendency of the protecting element A to curl up or assume such a condition that the side edge portions of same are arranged closer together, is offset or counteracted by the transversely-disposed stay C on the front side of the protecting element. Consequently, the protecting element A will retain its original concavo-convex shape and the transversely-disposed member B at the rear side of said protecting element will remain sufficiently taut to effectively absorb a shock or blow on said protecting element and hold said element spaced away from the part of the wearer's body that is to be protected.

If desired, pads D of felt or other suitable material can be arranged at the ends and at the side edges of the protecting element A and secured to said element by stitches or in any other suitable way, and means can also be used to hold the shock absorbing member B in a slightly bowed condition so as to make it conform approximately to the part of the wearer's body protected by the guard. In the event the guard is equipped with a means of the kind just referred to said means can be formed conveniently from a narrow strip of webbing or other suitable fabric E stretched longitudinally of the protecting element A at the rear side of same and arranged so that it crosses the shock absorbing member B and exerts pressure on said shock absorbing member in a direction to hold it in a bowed condition, as shown in Figure 3, the ends of the strip E being secured to the upper and lower ends of the protecting element A in any suitable manner, as for example, by stitches 1.

An athletic guard of the construction above described is light in weight, it is inexpensive to manufacture and it is equipped with a very efficient means for absorbing a shock on the protecting element of the guard that is bound to remain in an operative condition, due to the fact that the stay C which

is stretched taut across the front side of the protecting element holds said protecting element in shape and prevents it from curling up or assuming such a condition as to materially reduce the tautness of the shock absorbing member B of the guard.

Having thus described my invention, what I claim as new and desire to secure by Letters Patent is:

1. An athletic guard composed of a substantially rigid and inflexible protecting element of such cross-sectional shape that the side edge portions of same lie in a different plane than the intermediate portion of said element, a shock absorbing member stretched taut across the rear side of said protecting element and secured to the side edge portions of same, and a non-stretchable stay drawn taut across the front side of said protecting element and having its ends permanently secured to the side edge portions of said protecting element for counteracting the tendency of said element to assume such a condition as to materially reduce the tautness of said shock absorbing member.

2. An athletic guard consisting of a substantially rigid and inflexible protecting element, a taut shock absorbing member arranged transversely across the rear side of said protecting element and secured at its ends to said element, means for holding said shock absorbing member in a slightly bowed or curved condition so as to make it conform approximately to the part of the wearer's body against which it bears, and a non-stretchable stay drawn taut across the front side of said protecting element and having its ends permanently secured to the side edge portions of said element, for the purpose described.

3. An athletic guard composed of a curved protecting element formed from a substantially rigid and inflexible hard material, a fabric shock absorbing member stretched taut across the rear side of said element and permanently secured to said element so as to hold the same spaced away from the part of the wearer's body to be protected, a longitudinally-disposed fabric strip arranged crosswise of said transversely-disposed fabric member and connected to the protecting element for holding said transverse member in a bowed condition, and a non-stretchable stay stretched taut across the front side of said protecting element and permanently secured to said element.

WILLIAM P. WHITLEY.
